UNITED STATES PATENT OFFICE.

ROBERT F. CLARK, OF SALT LAKE CITY, UTAH.

WASHING-MACHINE.

1,388,800.

Specification of Letters Patent. Patented Aug. 23, 1921.

Application filed February 20, 1920. Serial No. 360,196.

To all whom it may concern:

Be it known that I, ROBERT F. CLARK, a citizen of the United States, and a resident of Salt Lake City, county of Salt Lake, and 5 State of Utah, have invented a certain new and useful Improvement in Washing-Machines, of which the following, together with the accompanying drawing, forms a full, clear, and exact specification.

10 This invention relates to washing machines, and its principal objects are to provide: first, a machine which shall be simple in construction, efficient in operation and economical in cost; second, a machine which 15 shall be easy to operate, and which may be driven by either hand or any other convenient form of power; third, a machine which shall not tear or otherwise injure the finest fabrics; fourth, a machine which shall 20 force the water thoroughly through all parts of the clothes in a series of agitating cycles, in each of which the water is alternately forced out of the clothes by a squeezing action and again drawn into the clothes by a 25 removal of the squeezing action; fifth, a machine adapted for thoroughly cleansing clothes by means of a swishing and squeezing action, as opposed to a rubbing and wearing action.

30 In attaining the objects outlined above, a tub is provided whose body portion preferably has the form of a triangular prism. Just inside one of the vertices of the triangle, formed by the sides of the tub, is a pivotally 35 disposed stem, whose axis may be more or less parallel to the planes of the sides. Extending out from the stem is a branching portion, which may have any suitable form, all the branches however, preferably lying 40 in one plane, the plane being movable around the axis of the stem, thus allowing it to be moved from side to side of the tub. The stem may extend through either the top or bottom of the tub, and may carry a rigidly 45 mounted arm or lever, by means of which, the branching portion may be given a reciprocating motion. The stem with its branching portion I choose to call an "agitator."

50 In using the machine the agitator is moved from side to side, the clothes on each side of the agitator being thereby alternately squeezed against a side of the tub, and swished through the water. The swishing action forces water through the clothes 55 and fills them with water, while the agitator squeezes the water out again. At each

stroke of the agitator, the clothes on one side are swished, and the clothes on the other side are squeezed. In this manner, the water can never acquire any rotary motion, but is only 60 dashed from one side to the other. The clothes are not rubbed against themselves nor against the tub, they are not twisted, they can neither be stretched nor strained, and hence the wear on the clothes, due to the 65 washing operations, is reduced to a minimum.

The features of this invention, upon which protection is desired, are collectively grouped in the appended claims. 70

In the drawing, which represents several of the preferred forms of this invention,

Figure 1, illustrates a plan view of the hand driven type;

Fig. 2, a plan view of the power driven 75 type;

Figs. 3 and 4, vertical sections, taken respectively, on line 3—3 in Fig. 1, and on line 4—4 in Fig. 2; and

Figs. 5 and 6, modified forms of the agi- 80 tator.

Referring to the drawing, (Figs. 1 to 4) the machine comprises the tub portion 10, the cover portion 11 and the branching portion 12 of the agitator.

85 In the hand driven type, the agitator may have the stem 13 with the enlarged shank 14, which latter may be journaled in the bearing 15 and be prevented from moving upwardly therein, by means of the collar 20. 90 The bearing 15 may have the flange 16, by means of which the bearing may be rigidly attached to the cover 11. The shank 14 may terminate in the head 18 which may carry the rigidly mounted handle or lever 19, 95 adapted for manipulation by the operator.

In the power driven type, (Figs. 3 and 4) the branching portion 12 of the agitator may have the stem 21 which terminates in the shank 22. The shank 22 may be journaled 100 in the stuffing-box 23, the latter being provided with the gland 24 for preventing the leakage of water from the tub. On the lower part of the shank 22 may be a rigidly mounted arm 25 having the eye 26, in which 105 may be pivoted the end of any suitable connecting rod (not shown). The connecting rod may be reciprocated by means of any well known mechanism suited to the purpose.

110 While the preferred form of the branching portion of the agitator is shown at 12,

in Figs. 3 and 4, yet the forms thereof may be considerably varied, as represented for instance, in Figs. 5 and 6, these forms having the stems 27 and 28 respectively, and the shanks 14, being adapted for use with the hand driven type already described. The same modifications in the design of the agitator may be applied to the power driven type.

- 10 In operation, the agitator is moved back and forth in the directions of the arrows in Figs. 1 and 2. The agitator, at the end of each stroke, occupies approximately the positions indicated by the dotted lines at 29 and 30 in Fig. 2, the clothes on one side of the agitator being squeezed between the agitator position 29 and the wall 31 of the tub, while the clothes on the other side of the agitator are simultaneously allowed to draw 20 in the water. At the next stroke, the clothes on the side of the agitator between the position 30 and the wall 31 are squeezed while the clothes on the side between the position 30 and the wall 31 simultaneously draw in 25 the water. The cycles described, alternate with each other indefinitely.

It will be noted in Fig. 2, that the agitator in its movements, sweeps over areas having the shapes of sectors of a circle concentric 30 with the axis of the stem, and bounded by radii more or less parallel to the side walls of the tub.

For convenience in manufacturing and cleaning, the sharp vertices of the theoretical triangular prism may be rounded off, resulting in the general shape shown in Figs. 35 1 and 2.

What I claim as new, is:

1. In a washing machine, the combination 40 with a horizontal tub portion having sides lying in three intersecting vertical planes, of an agitator pivotally supported near the vertex formed by two of the intersecting planes, the said agitator being adapted to oscillate between the said two planes; and the third plane being tangent to an arc concentric with, and lying somewhat outside of, the arc described by the oscillating extremity of the said agitator, the point of tangency 45 being approximately at the center of the said arc.

2. In a washing machine, a tub portion comprising a bottom with three side walls rising vertically therefrom, the said walls lying in 55 three intersecting planes, a bearing supported by the said bottom, an agitator composed of a plurality of consecutive U-portions with an integral stem forming a part of the first U-portion, the said stem being mounted in 60 the said bearing, the said bearing being so located that the agitator may be oscillated in a manner that will cause it to sweep over an area having the form of the sector of a circle, the bounding radii of the said sector 65 being approximately parallel to two of the

said side walls, and the third side wall being tangent to an arc concentric with, and lying just outside, the arc described by the oscillating extremity of the said agitator, the point of tangency being approximately 70 at the center of the said arc.

3. In a washing machine, the combination with a tub portion having two approximately vertical side walls lying in intersecting planes, of a branching agitator 75 pivotally mounted between the said walls, the said agitator being adapted to swing from a position approximately parallel to one of the side walls to a position approximately parallel to the other side wall; 80 a third side wall lying in a plane tangent to an arc concentric with, and lying just outside, the arc described by the oscillating extremity of the said agitator, the point of tangency being approximately at the center 85 of motion of the said agitator; and curved wall portions adapted to join the said three wall portions to each other.

4. In a machine of the character described, a tub portion having walls lying approximately in two intersecting planes, an agitator having an oscillating disposed axial member, the axis of the said member being located between, and approximately parallel to line of intersection of, the 90 said planes; the said agitator comprising, further, a plurality of U-portions arranged in series, originating at, and integral with, the said axial member, all of the said parts being so disposed that the 95 said U-portion series may be brought into approximate parallelism with each of the said planes, and means for moving the said agitator back and forth between the said walls, whereby washable units may be carried 100 by the agitator, and the said units be compressed between the said agitator and the said walls with the accompanying result that the portion of the said washable units nearest the said oscillating axis shall have a 105 minimum agitation, while the portion of the said washable units farthest from the said axis shall have a maximum agitation.

5. The combination with a tub portion having three vertically intersecting side 110 walls, of an agitator having a stem with an axis more or less parallel, and close to the line of intersection, between two of the said walls, the said agitator adapted to be oscillated around the said axis, and comprising a 115 series of consecutive U-shaped branches integral with the said stem and lying more or less in the same plane; and means for oscillating the said agitator; the said combination being so constituted that the agitator 120 may carry a bunch of clothes and alternately press the said bunch against the two said walls.

6. A tub portion having three vertical 125 walls, two of the said walls lying in planes 130

which intersect each other, thereby forming an angular space between the said two walls, an agitator formed of a plurality of U-shaped branching members consecutively disposed, 5 lying more or less in one plane and located in the angular space, a suitably mounted stem integral with, and adapted to support, the said branching members in such manner that they may be moved from a position 10 more or less parallel to one of the said in-

tersecting planes to a position more or less parallel to the other intersecting plane, the said agitator being thereby adapted to carry a bunch of clothes and to alternately press opposed portions of the said bunch against 15 the said two walls; and means for imparting an oscillating motion to the said agitator.

In testimony whereof I sign my name hereto.

ROB'T F. CLARK.
